Achlegsdorff

UNITED STATES PATENT OFFICE.

SAMUEL W. WEBER, OF BROOKLYN, AND LEONARD HORINKO, OF NEW YORK, N. Y.

CONVERTIBLE CHAIR.

1,210,878.

Specification of Letters Patent. Patented Jan. 2, 1917.

Application filed November 20, 1915. Serial No. 62,449.

To all whom it may concern:

Be it known that we, SAMUEL W. WEBER and LEONARD HORINKO, citizens of the United States, and residents, respectively, 5 of New York, borough of Brooklyn, county of Kings, and State of New York, and of New York, in the county of New York and State of New York, have invented certain new and useful Improvements in Convertible Chairs, of which the following is a specification.

This invention relates to convertible chairs particularly to a chair which may be converted into a bed or couch.

15 To effect economy in space, a variety of folding beds and couches have been brought upon the market. All of these have proved more or less objectionable. Some when folded form an odd object which serves no 20 useful purpose and may be recognized immediately as a folding bed. Others of the so-called davenport type are very heavy, bulky and expensive, while still others sacrifice comfort for economy in space.

25 In carrying out our invention, we provide a comfortable arm chair which when unfolded is converted into a thoroughly comfortable bed with a short head rest which may be raised or lowered to suit the 30 fancy of the user.

The various novel and advantageous features of the invention will more fully appear from the following detailed description and the novel construction and combination of elements will be particularly 35 pointed out in the claims.

In the drawing illustrating a preferred embodiment of the invention, Figure 1 is a side elevation of an arm chair embodying the invention, the chair being in folded position. Fig. 2 is a plan view of the bed when unfolded. Fig. 3 is a longitudinal sectional elevation of the bed in the position shown in Fig. 2. Fig. 4 is a figure similar 45 to Fig. 3 in side elevation. Fig. 5 is a section taken along line 5—5 of Fig. 2.

Referring in detail to the drawing, the improved convertible chair is formed in three main sections comprising a base section 50 10 having suitable legs 11. At the forward edge of the base section is hinged an arm and seat section 12 and at the rear edge of the base section is hinged a back section 13. When the chair is folded as in Fig. 1, the 55 seat and back sections are held in position by any suitable engaging means preferably

short latches 14, coupling the sides of the back section with the adjacent vertical portion of the arm section. Hinged at the rear of the back section 13, preferably adjacent 60 the upper end thereof, are legs or supporting members 15 and hinged at the front of the back section is an adjustable head rest 16. When the chair is converted into a bed or couch, the latches 14 are disengaged and 65 the seat section 12 and the back 13 swung downward into the positions illustrated in Figs. 2, 3 and 4, the back being then supported by the legs 15 which are swung into vertical position. These legs 15 may be 70 held rigidly in position by means of a lug 17 engaging a hinged extension 18 provided on the upper edge of the leg frame, the head rest being then in the raised adjustment. In case it is desired to lower the head rest so 75 as to form a perfectly flat bed as indicated in dotted lines in Fig. 3, the legs 15 may be braced by rods 19 extending from the legs to the back section and detachably engaging the same. To take the weight off 80 the hinge, a bracket 20 may be formed upon the rear of the base section 10 to support the adjacent edge of the back section when the same is lowered.

It will be understood that in the unfolded 85 position, the seat section 12 is at the foot of the bed, the base section is at the middle while the back section 13 is at the head of the bed, the junction of the base and back sections being in a position approximately 90 where the back of the person would lie. Spring sections 21, 22, 23 are secured respectively to the seat, main and back sections and over these springs suitable 95 cushions are placed which in the folded chair 95 constitute the cushions or upholstery of the chair, but in the converted bed form a mattress.

To prevent the formation of a hard spot in the bed by the frame work at the junction of the main section and the back section, downwardly bowed cross pieces 24 and 25 of metal tubing or other suitable material are provided to unite the respective sides of the main and back sections. The 100 spring sections 22 and 23 may be joined together in any suitable manner, as by short spiral springs 26, thus maintaining the tension of the spring sections and at the same time permitting the parts to be readily 105 folded and unfolded with perfect freedom.

110 It will thus be seen that we have pro-

vided a chair which can be converted into a thoroughly comfortable bed, as, when the chair is unfolded, a perfectly level bed is formed with a small head rest which can be raised or lowered to suit the requirements of the user. The head of the bed is well supported by the swinging legs and the latter are locked in proper position. No objectionable hard spots are formed in the spring, as the framework is bridged over in the novel manner heretofore described.

Having thus fully described our invention, what we claim as new and desire to secure by Letters Patent is—

- 15 1. A convertible chair comprising a base section, a back section hinged thereto, said back section being adapted to be swung back to form the head of a bed, legs hinged to the back section to support the same on the floor in extended position, a head piece on the back section, and means on the head

piece engaging the legs to hold them in position when supporting the back section.

2. A convertible chair comprising a base section, a back section hinged thereto adapted to swing down to form the head portion of the bed, hinged legs mounted on the back section, a pivoted extension provided on the legs, a swinging head piece, and means on said head piece to engage the extension to hold the legs in position when supporting the back and to maintain the head piece in raised adjustment.

Signed at New York city, in the county of New York and State of New York, this 35 16th day of November A. D. 1915.

SAMUEL W. WEBER.
LEONARD HORINKO.
